UNITED STATES PATENT OFFICE.

JAMES M. KING, OF BLUE SPRINGS, NEBRASKA, ASSIGNOR TO CHARLES A. VAN PELT, OF SAME PLACE.

SEED PRESS-DRILL.

SPECIFICATION forming part of Letters Patent No. 612,043, dated October 11, 1898.

Application filed June 25, 1897. Serial No. 642,322. (No model.)

To all whom it may concern:

Be it known that I, JAMES M. KING, a citizen of the United States, residing at Blue Springs, in the county of Gage and State of Nebraska, have invented a new and useful Seed Press-Drill, of which the following is a specification.

My invention relates to improvements in seed-drills in which I have embodied mechanism for pressing the soil upon the seed after it has been planted in the furrow in the general manner indicated by United States Letters Patent No. 495,495, granted to me April 18, 1893.

15 It is my purpose to provide a machine which, generally stated, operates to open the furrow, deposit the seed therein, pulverize the soil, cover up the seed, and press the soil firmly upon the seed, all of which is effected to plant 20 the seed at a uniform depth in all the furrows without regard to the roughness and unevenness of the soil.

25 My improved machine embodies an improved construction of the colter-carrying means, whereby the journals may be kept in a well-lubricated condition; mechanism for raising or lowering the front of the drill, in which the adjusting device is wholly under the control of the driver seated on the 30 machine, so that the machine may be thrown out of operation when going to or from the field or turning at the end of a furrow, as well as provide for regulating the depth at which the seed is planted in the soil; to 35 means for regulating the quantity of seed which may be deposited in the ground by each drill; mechanism for automatically throwing out of operation the seed-dropping devices when the front part of the frame is 40 raised, and an improved construction of the means for carrying the presser-wheels, so as to reduce the number of supporting devices for such wheels; and the invention further consists in the novel combination of devices and in the construction and arrangement of parts, which will be hereinafter fully described and claimed.

45 To enable others to understand my invention, I have illustrated the preferred embodiment of the same in the accompanying draw-

ings, forming a part of this specification, and in which—

Figure 1 is a plan view, with the hopper in dotted lines, of a seed press-drill constructed in accordance with my invention. Fig. 2 is 55 an end elevation. Fig. 3 is a vertical longitudinal sectional view on a plane at one side of the seat-carrying frame and showing the means whereby the front end of the drill may be raised or lowered. Fig. 4 is a perspective 60 view of a part of the seat-frame with the means for attaching the same to the front and rear shafts of the machine, together with the means for adjusting the drills and colters. Fig. 5 is a vertical transverse sectional view 65 on the plane indicated by the dotted line 55 of Fig. 1. Fig. 6 is a longitudinal section through the hopper and machine and on a plane at one side of the transmitting-gearing between the press-wheel axles and the feed- 70 roll shaft of the seed-dropping devices. Fig. 7 is a detail view of one of the drills with its spring-hanger and the colters. Fig. 8 is a side view, partly in section, of the devices shown by Fig. 7. Fig. 9 is a vertical trans- 75 verse sectional elevation through the drill to show the oil-feed tube, the axles, and the bolt of said drill. Fig. 10 is a detail view of one of the hanger-springs, illustrating the axle to carry a pair of the press-wheels. Fig. 11 80 is a detail view of one of the feed-cups with a part of the feed-roll shaft, the feed-roll, and the smooth-faced follower for said feed-roll; and Fig. 12 is a sectional elevation taken longitudinally through the parts shown by Fig. 85 11. Fig. 13 is a detail perspective view of the adjusting mechanism for the feed-roll shaft and to indicate the quantity of seed dropped by the seed-distributing devices. Fig. 14 is an enlarged plan view of the left- 90 hand part of Fig. 1, showing parts skeletonized and illustrating more particularly the transmitting mechanism between an adjacent pair of press-wheels and the feed-roll shaft. Fig. 15 is a sectional elevation on the 95 plane indicated by the dotted line 15 15 of Fig. 14, and Fig. 16 is a similar sectional elevation on the plane indicated by the dotted line 16 16 of Fig. 14.

Like numerals of reference denote corre- 100

sponding parts in all the figures of the drawings, referring to which—

1 designates the main shaft or axle of the machine, and 2 is a rock-shaft which is arranged in front of the main shaft in a plane parallel therewith and is adapted to be raised or lowered with the colters, as will hereinafter appear.

The main shaft or axle 1 and the transverse rock-shaft 2 are connected together by end bars 3 3, which also furnish supports for the transverse seed - hopper 4, the latter being bolted or otherwise rigidly secured to said end bars 3 3. The main shaft or axle 1 of the machine is rigidly attached to the rear extremities of the end bars 3 by the split castings 5 5, the latter being bolted to the bars 3 and having jaws formed by the split portions of said castings, which jaws receive the ends of the main shaft or axle 1 and are compressed thereon by bolts which operate to make the jaws firmly grip and hold the main shaft or axle 1. The front rock-shaft 2 has its ends fitted loosely in the castings 6, which are attached to the front ends of the bars 3 to serve as journal-boxes for the front rock-shaft 2.

The tongue of the machine is indicated by the numeral 6', and the rear end of this tongue is fitted on a bolt 7, which is supported in a pair of plates or ears 8, cast integral with a sleeve 9, which is fastened rigidly to the rock-shaft 2 at the center thereof.

Fitted loosely on the rock-shaft 2 at points on opposite sides of the sleeve 9, which supports the rear end of the draft-tongue, are the castings 10 10, to the rear ends of which are bolted the forward ends of the horizontal metallic bars 11 11, which are arranged parallel to each other and extend rearwardly beyond the main axle or shaft 1 for a suitable distance to form the lower part of the seat-supporting frame, said bars 11 11 being bolted at intermediate points of their length to castings 12 12 on the main shaft or axle 1.

The seat 13 is supported by an upright frame consisting of the bars 14 and the braces 15. The bars 14 are attached at their front ends to the castings 12 on the main shaft or axle 1, and said bars 14 extend upwardly and rearwardly over the lower part or bars 11 of the seat-frame, the rear ends of the bars 14 being brought together to provide a shank 14', to which the seat 13 is attached. The braces 15 are fastened to the bars 11 and the upright bars 14 at points in front of the seat, as shown.

It will be observed that the main axle 1 and the front rock-shaft 2 are connected together at their ends by the end bars 3 and at the middle by the bars 11, so that the parts 1 and 2 are held in their proper parallel relation and the framework of the machine presents a substantial and rigid structure.

I will now proceed to describe the mechanism for raising or lowering the front part of the drill.

To the rock-shaft 2 is rigidly fastened the

castings 16 17, which are arranged at points outside of the castings 10, and to these castings are rigidly bolted the lifting-bars 18 18. These lifting-bars are rigidly attached to the fast castings 16 17 at points intermediate of their length, and the front ends of said lifting-bars are converged inward toward the draft-tongue 6', so that they fit against opposite sides of said tongue to be attached thereto by a transverse bolt 19. These lifting-bars 18 extend rearwardly below the main axle 1, and to the rear extremities thereof are bolted the lower ends of vertical links 20. Attached to lower part of the seat-frame formed by the bars 11 are the journal-bearings 21, in which is mounted a transverse short rock-shaft 22, and to the ends of said shaft is rigidly fastened the rocking arms 23, having the upper ends of the links 20 pivotally attached to their outer ends. To this short rock-shaft 22 is attached a controlling-lever 24, which carries a spring-operated dog 25, connected by a link 26 to a hand-grip 27, and said spring-operated dog is adapted to engage with any one of a series of notches or seats formed in the peripheral edge of a holding-segment 28, which is fastened to one of the bars 11 in position for the dog to engage therewith at any point of adjustment of the lever 24. When the lever 24 is thrown to the rear, the rock-shaft 22 is turned to raise the links 20 and the rear ends of the lifting-bars 18, attached thereto, and as these lifting-bars are bolted firmly to the rock-shaft 2 and to the rear end of the tongue and as the tongue itself is connected to the rock-shaft and braced laterally by the lifting-bars the front part of the drill is raised out and above the ground and carried in that position, the weight being sustained by the press-wheels connected with the main shaft or axle 1 and on the front extremity of the draft-tongue, which rests in the neck-yoke, to which the team is hitched. To lower the front part of the drill, the lever 24 is thrown forward to lower the links 20 and the lifting-bars, thus easing up on the draft-tongue and neck-yoke and allowing the colters and drills to penetrate the ground, the depth of such penetration being controlled by the adjusting of the lever 24.

The drills are represented by the numerals 30, and they are arranged in series and in parallel relation to each other on the front shaft 2 of the machine, each drill being carried by a spring-hanger 31, which is attached to the drill and to the shaft 2 independently of the other spring-hangers of the series provided for the number of drills used in the machine. I construct each drill in a single casting in a novel form to support a pair of colter-disks and for the attachment of the spring-hanger securely thereto, and each drill is furthermore constructed with a lubricating means for the stub-axes, on which the colter-disks are fitted. The drill is cast in a single piece, with a bracket 32 on its front side

and with the short stub-axes 33 33, which extend laterally beyond the sides of the drill. The drill is provided with the usual seed-conducting passage 34, and in the operation of casting the drill I embed therein and form as an integral part thereof a vertical lubricant-conducting tube 35, which protrudes at its upper end above the horizontal face of the bracket 32, the lower end of said oil-tube discharging to a transverse oil-duct 35', by which the lubricant is conducted to the stub-axes 33 of the colter-disks 36 37. These colter-disks are clamped loosely against the sides of the drill, and they occupy inclined positions to the drill and to each other, substantially as shown by my Patent No. 448,349, dated March 17, 1891. The spring-hanger 31 is fitted snugly upon the horizontal face of the bracket 32, and it is rigidly and firmly united thereto by suitable bolts, and said hanger is curved upwardly and rearwardly to enable it to be attached to the front rock-shaft 2 of the machine. The front end of the hanger is rigidly attached to the upper side of the front rock-shaft 2, and it extends over and in front of the shaft, and thence rearwardly to the bracket 32 of the drill, as shown.

In the drawings I have shown a series of ten drills and their complemental springs, which are attached to the front rock-shaft 2 independently of each other, so as to sustain the drills independent and allow them to have the desired play without respect to one another.

The colter-disks are fitted loosely on the stub-axle, and this axle is made of hollow form to accommodate a transverse bolt 36', which passes through the stub-axe 33 and has the steel washers 37' secured on its ends to laterally confine or clamp the colter-disks to the axle.

The press-wheels, which serve to cover the seed deposited in the furrows and to pack the soil upon the seed, are indicated at 40 in the drawings, and one of these press-wheels is arranged to follow in the path of a pair of the colter-disks and one of the drills 30. In my prior Letters Patent No. 495,495 I show each press-wheel carried by a separate spring, the number of which corresponds to the number of wheels used, as well as the number of drills and colters; but in my present invention I have constructed the press-wheel-carrying devices in a novel manner to reduce the number of springs required to support the proper number of press-wheels with which the machine is to be equipped. According to this part of my invention I mount the press-wheels 40 in pairs on a series of short axles 41, which are fitted centrally to the rear lower extremities of the carrying-springs 42. The springs or spring-hangers 42 are curved throughout their length, and their upper ends are fastened to the main shaft or axle 1, said spring-hangers being curved over in front of the shaft 1 and thence extended rearwardly and downwardly for suitable distances. The lower rear

ends of the spring-hangers 42 are rigidly bolted to the bearings 43, which are arranged to permit the short axles 41 to pass through the same, the bearings thus constituting the housings for the axles 41. These axles extend beyond their housings to have their spindles exposed and to receive the hubs of the press-wheels, the latter being confined on the axle-spindles by any suitable means.

By supporting the press-wheels in pairs on a short axle which is common to two wheels I am enabled to reduce by half the number of axles, the supports or boxings therefor, and the spring-hangers, thus simplifying the construction.

To the bottom of the seed-hopper 4 is rigidly attached a series of feed-cups 45, which communicate with the interior of the hopper 85 through suitable openings provided in the bottom of the same. These seed or feed cups are of the usual or any preferred construction, with an open side wall at one side and with a flanged wall at its other side to receive the notched ring 46, through which passes and is journaled the fluted feed-roll 47, which is fitted to the notched ring to rotate therewith and to have a limited endwise movement with the feed-roll shaft 48. This shaft 48 is of square or other angular form in cross-section, and it extends throughout the length of the feed-hopper 4 and through all of the series of feed-cups and the fluted rolls in said cups. The feed-roll has a square opening through which passes the square shaft to couple the feed-rolls to the shaft and to make the rolls rotate with the shaft, whereby all the rolls are operated from a common shaft, which, however, is capable of a limited endwise movement to adjust the feed-rolls in the seed-cups and to vary the area of each feed-roll within the feed-cup, so as to regulate or control the quantity of seed deposited by each dropping appliance of the series provided on the outside of the bottom of the hopper 4. Each feed-roll is sustained at one end by the notched bearing-ring 46, and at its other end it is connected in a novel manner with a plain face or smooth cylindrical roll or follower 49, that is movable endwise with the fluted feed-roll, but is loosely mounted on the shaft 48. The roll or follower 48 is hollow, and at its inner end it is formed with an inwardly-extending radial flange 48', and through the flange 48' of the follower passes a cone 50. This cone has an angular aperture 49' to receive the angular feed-roll shaft 48, and thus connect said cone to the shaft to rotate or turn therewith, while the smooth-faced roll or follower is fitted loosely on the angular feed-roll shaft.

The fluted feed-roll and the cone 50 are held on the shaft 48 against endwise displacement by means of spring-cotters 51 51, which pass through openings in the shaft 48, and these cotters hold the cone and the smooth-faced roll close up to one end of the fluted feed-roll 47. The smooth-faced roll or follower 49 is adapted to abut against an annular flange 52,

provided on the cone 50, and the cone is thus held against endwise movement in one direction by the flanged cone 50 and in the opposite direction by the end of the fluted feed-roll, against which it abuts when the parts are in operative relation. On the periphery of the smooth-faced roll or follower 49 is provided a longitudinal key or rib 53, which is fitted in a notched seat 54 in the bottom of the feed-cup, and this key is adapted to slide with the roll 49 in the key-seat 54 when the shaft is adjusted endwise to move the fluted feed roll or follower 47 and the smooth-faced roll 49 endwise in the feed-cup.

15 It will be observed that the fluted feed-roll 47 and the cone 50 are connected to the shaft 48 to rotate therewith at all times; but the smooth-faced roll or follower is loosely fitted on the shaft and is connected by the rib or key 53 to the feed-cup to normally occupy a stationary position, the smooth-faced roll being held up against the feed-roll by the cone. At the same time the fluted and smooth-faced rolls are movable with the shaft 48 in its endwise adjustments, so that the feed-roll 47 may be partially projected or extended through its notched bearing-ring 46 and the smooth-faced roll correspondingly moved into the feed-cup, or vice versa, whereby the area of the fluted 25 feed-roll exposed within the feed-cup may be varied to regulate the quantity of seed discharged from the feed-cup by the fluted feed-roll.

30 The feed-cups are connected with the drills by the hose or spouts 55, the upper ends of which are suitably attached to the feed-cups, while the lower ends of said hose or spouts fit loosely in the vertical seed-conduits provided in the drills.

35 40 I will now proceed to describe the means for adjusting the feed-roll shaft 48 endwise. To the bottom of the hopper 4 is rigidly fastened a supporting-plate 56, which is cast in a single piece with screw-holes 57 and with an arc-shaped slot 58. This supporting-plate is preferably of quadrant shape, and to one end of the plate is fulcrumed a controlling-lever 60, the lever being fulcrumed on the plate by a suitable pin or bolt 59. Near its 45 free end the lever is slidably attached to the supporting-plate by means of a shifting bolt 61, which passes through the slot 58 and the lever 60 and which serves to hold the lever in place on the supporting-plate 56. This lever 60 carries a bracket 61', which is attached centrally to the lever at a point intermediate of its length by a pivotal bolt 62, and this bracket is provided with recessed ears or flanges 63, the latter being arranged at the 50 ends of the bracket to embrace an adjusting sleeve or collar 64 on the feed-roll shaft 48. The adjusting sleeve or collar 64 has an angular opening to enable it to fit snugly on the shaft to rotate therewith, and endwise movement of this collar or sleeve is prevented by the cotters or keys 65, which pass through openings in the shaft 48 and abut against the

ends of the adjusting collar or sleeve. The collar or sleeve thus rotates with the shaft, but is held against endwise movement thereon, 70 and the bracket 61' engages loosely with the adjusting collar or sleeve to permit the latter to rotate with the shaft and within the bracket without affecting the position of the controlling-lever. On the hopper 4 is attached a 75 graduated plate 66, to which is slidably connected an indicator-plate 68 by a bolt which passes through a slot 67 in plate 68, the latter being operatively connected by a link 69 to the controlling-lever 60. The link 69 is 80 preferably pivoted at one end to the pivoted bracket 61', and its other end is pivoted directly to the slideable indicator, as shown. The lever can be moved by the driver to shift the bracket 61' and move the adjusting collar or sleeve, thus moving the feed-roll shaft 48, and with it the series of feed-rolls and smooth-faced rolls, to vary the quantity of seed deposited by the fluted feed-rolls, and at the same time the lever operates the link 69 to 85 move the indicator 68 to a different position on the graduated plate to make the latter show to the operator the adjustment of the feed-rolls and the quantity of seed said rolls are depositing in the drills. The controlling- 90 lever is thus operatively connected with the feed-rolls and with the indicator mechanism, and the parts move in synchronism to regulate the seed discharge and to indicate on a dial the adjustment of said parts. 95

100 I will now proceed to describe in detail the transmitting-gearing between two adjacent press-wheel shafts and the feed-roll shaft, reference being had more particularly to Figs. 14, 15, and 16 in connection with Figs. 1, 2, 3, 5, and 6.

105 The feed-roll shaft is driven by transmitting mechanism from two adjacent axles of two pairs of carrying or press wheels. On the main shaft or axle 1 of the machine is bolted a pair of hangers 70, provided with bearings, in which is journaled a short counter-shaft 71. On this counter-shaft is loosely mounted a sprocket-pinion 72, provided at its ends with clutch-faces 73. On opposite sides 110 of the sprocket-pinion 72 is arranged the slideable sprocket-wheels 74, 75, which are provided with the clutch-faces 76 and are normally pressed into engagement with the clutch-faces 73 of the pinion 72 by means of 115 the coiled springs 77, which are fitted on the counter-shaft 71. The sprocket-wheel 74 is connected by a sprocket-chain 78 to a sprocket-wheel 79 on the end of the axles of a pair of press-wheels; but the other slideable sprocket-wheel 75 is connected by a sprocket-chain 80 with a sprocket-wheel 81 on the end of another axle of an adjacent pair of press-wheels. Should one pair of press-wheels be 120 in a position where it will fail to rotate the slideable sprocket on the counter-shaft 71, the other pair of press-wheels will serve to drive the other sprocket-wheel on said counter-shaft, and thus the sprocket-pinion 72 will 125

be rotated by one or the other pair of press-wheels and the machine adapted for proper operation. The sprocket-pinion 72 operates a transmitting sprocket-chain 84, which passes around a sprocket-wheel 84' on the feed-roll shaft 48 in a manner to rotate or drive the latter.

In connection with the sprocket-wheel 84' on the feed-roll shaft 48 and with the vertically-adjustable front part of the planter, I have combined novel mechanism for throwing out of operation the feed-roll shaft when the colters and drills are raised out of the ground—as, for instance, when the machine is traveling to or from the field or turning at the end of the furrow. To this end I provide the sprocket-wheel 84' with a clutch-face 85 on one side thereof and mount said sprocket-wheel 84' loosely on the feed-roll shaft 48. Adjacent to the sprocket-wheel 84' is arranged a shiftable clutch 85', which is slidably fitted on the feed-roll shaft 48 to rotate therewith, and this clutch is provided at one end with an annular groove 86, in which fits the forked or rounded end of a shipper-arm 87, the latter being attached to one end of a shipper-rod 88. This shipper-rod is slidably fitted in suitable bearings on the hopper 4, and said rod is normally impelled by a coiled spring 89 in a direction to move the clutch 85' into engagement with the sprocket-wheel 84', thus making the latter fast with the feed-roll shaft to rotate the latter. The end of the shipper-rod opposite to the end carrying the shipper-arm is formed into or provided with an eye or loop 90, which may be slidably fitted in a suitable guide on the hopper 4, and through this eye or loop of the shipper-rod passes a vertical operating bar or rod 91. The lower end of the vertical rod or bar is rigidly fastened to one of the lifting-bars 18, and said vertical rod or bar is formed or provided at an intermediate point of its length with a swelled or enlarged section, forming a wedge or cam 92, which is adapted on the upward movement of the lifting-bar 18 to pass into and act against the loop or eye of the shipper-rod 88. As the wedge or cam 92 of the vertically-movable rod or bar 91 binds against the eye or loop 90 of the shipper-rod 88 the latter is drawn endwise against the tension of the spring 89 to move the shipper-arm 87 sidewise and adjust the clutch 85' on the feed-roll shaft 48 to withdraw said clutch from engagement with the sprocket-wheel 84', thus making the said sprocket-wheel 84' loose on the shaft 48 and allowing the latter to remain at rest. When the colters are lowered by adjusting the hand-lever 24 and the lifting-bars 18 drop down to the normal position, the vertically-movable rod 91 is pulled down with the lifting-bar 18, to which it is attached, and thus the wedge or cam 92 of the bar 91 is withdrawn from the eye or loop of the shipper-rod to permit the spring 89 to return the shipper-rod to a position where the arm 87 impels the

clutch in engagement with the sprocket-wheel 84'.

It will be observed that the feed-roll shaft 48 is thus automatically thrown out of operative connection with its driving mechanism when the drills and colters are raised by the adjustment of the hand-lever; but when the parts are restored to normal active position the feed-roll shaft is again thrown into operative relation with its driving mechanism.

It is thought that the operation of my invention will be readily understood from the foregoing description taken in connection with the drawings.

I am aware that changes in the form and proportion of parts and in the details of construction of the devices herein shown and described as the preferred embodiment of my invention may be made by a skilled mechanic without departing from the spirit or sacrificing the advantages of my invention, and I therefore reserve the right to make such modifications as fairly fall within the scope of the invention.

Having thus fully described my invention, what I claim as new, and desire to secure by Letters Patent, is—

1. In a seed press-drill, the combination with a frame and a series of front spring-hangers carrying drill-tubes, of another series of rear spring-hangers of less number than the first series of spring-hangers and attached to the frame in alternate relation to the front hangers and adapted for vertical yielding movement independently of each other and of the first series of hangers, and press-wheels arranged in pairs to follow in the wake of the drill-tubes, one pair of press-wheels being carried by each hanger of the rear series thereof, substantially as described.

2. In a seed press-drill, the combination with a frame, and a front series of spring-hangers carrying drill-tubes, of a rear series of spring-hangers of less number than the first series of hangers and attached to the frame in alternate relation to said front hangers for vertical yielding movement or play independently of each other and of the first series of hangers, an axle rigid with each of the rear spring-hangers, and a pair of press-wheels journaled on the axle of each of said rear hangers, said press-wheels arranged to travel in the wake of the drill-tubes on the front hangers, substantially as described.

3. In a seed press-drill, the combination with front and rear shafts, and a series of front hangers attached to the front shaft and carrying drill-tubes and colters, of a series of rear spring-hangers attached to the rear shaft in the intervals between the attachment of the front hangers and adapted for vertical yielding movement or play independently of each other and of the front hangers, a series of axles each rigidly attached to one of the rear spring-hangers and provided with spaced boxings, and press-wheels journaled in pairs

on the axles of the rear spring-hangers, substantially as described.

4. In a seed-planter, the combination with a spring-hanger, 42, of the boxing 43 united 5 rigidly to said hanger, a transverse axle carried by said boxing and projecting at both ends laterally therefrom, a pair of press-wheels journaled on the protruding ends of said axle and spaced in relation to each other by the 10 intermediate boxing, and suitable retainers on the axle to hold the press-wheels in position, substantially as described.

5. The combination with front and rear axles or shafts, of a draft-tongue attached to 15 the front shaft, a seat-frame loosely attached to the front shaft and rigidly connected with the rear axle, lifting-bars attached to the front shaft and to the draft-tongue, an operating-shaft journaled on the seat-frame and oper- 20 atively connected with the lifting-bars, and a controlling-lever with means for locking the same in place, as and for the purposes de- scribed.

6. The combination with a front shaft, and 25 a rear axle, of a draft-tongue attached to said front shaft, a seat-frame loosely connected to the front shaft and rigidly fastened to the rear axle, lifting-bars attached to the tongue and to the front axle and extending rear- 30 wardly beneath the rear axle, an operating- shaft journaled on the seat-frame and pro- vided with rock-arms, links connecting said rock-arms with the lifting-bars, a hand-lever attached to the rock-shaft, and a segment 35 with locking means with which the hand-lever is adjustably connected, as and for the purposes described.

7. The combination with a feed-cup, a shaft and a fluted feed-roll fitted at one end to the 40 shaft, of a bearing-cone arranged on the shaft partially within the end of the feed-roll to afford a bearing for said roll and provided with an annular flange at its end opposite to the feed-roll, and a smooth roll or follower 45 having an inwardly-extending flange which fits between the open end of the feed-roll and the flange of the bearing-cone, whereby the follower is coupled by the bearing-cone to the feed-roll, substantially as described.

50. 8. The combination with a feed-cup, a shaft and a fluted feed-roll fitted at one end to the shaft, of a bearing-cone arranged on the shaft partially within the open end of the feed-cup and having at one end an annular flange 52, 55 a smooth roll or follower provided with an inwardly-extending flange which fits between the end of the feed-roll and flange of the bearing-cone, and the retainers 51 attached to the shaft and fitted against the feed-roll 60 and the bearing-cone, substantially as de- scribed.

9. The combination with an endwise-mov- 65 able feed-shaft, of a fixed supporting-plate, a lever fulcrumed on said plate and having a free end projecting rearwardly therefrom and beyond the feed-shaft, and an adjusting col-

lar or sleeve journaled to rotate freely on the lever at a point between its free end and the fulcrum and connected directly to the feed-shaft to travel and rotate therewith, substan- 70 tially as described.

10. The combination with an endwise-mov- able feed-shaft, of a lever, a bracket swivel- 75 ed to the lever at a point intermediate of its length, and an adjusting-sleeve movable with the feed-shaft and journaled in the bracket to rotate freely therein, substantially as described.

11. The combination with a feed-shaft, of a supporting-plate, a lever fulcrumed at one end on said plate and slidably attached, near its free end, to said plate, a swiveled bracket carried by said lever, and an adjusting-collar fitted to the shaft to move therewith and loosely journaled in and connected to said 85 bracket to be adjusted by the lever and the bracket, substantially as described.

12. The combination with a feed-shaft, of a controlling-lever, a collar or sleeve at- 90 tached to the shaft to move therewith, a swiv- 95 ed bracket carried by the lever and loosely engaged with said adjusting collar or sleeve, an indicator-plate, a slidable indicator sup- ported by said plate, and means for connect- ing the slidable indicator with said lever, sub- stantially as described.

13. The combination with an endwise-mov- able, feed-roll shaft, of an adjusting collar or 100 sleeve attached thereto, an indicator-plate, a 105 slidable indicator, a controlling-lever, and a bracket pivoted to said lever, linked to the indicator, and operatively connected with the adjusting collar or sleeve, as and for the pur- 110 poses described.

14. The combination with an axle or shaft, 105 and a feed-roll shaft, of spring-hangers each carrying a pair of presser-wheels, a counter- shaft operatively connected with the axles of adjacent pairs of presser-wheels, and trans- 110 mitting-gearing between said feed-roll shaft and the counter-shaft, as and for the purposes described.

15. The combination with an axle or shaft, 1, and a feed-roll shaft, of a counter-shaft journaled on the axle or shaft, 1, a set of 115 clutch-formed sprocket-wheels on said counter-shaft, two of which sprocket-wheels are geared to an adjacent pair of axles carrying press-wheels, a sprocket on the feed-roll shaft, and a sprocket-chain connecting the 120 third sprocket on the counter-shaft with the sprocket on the feed-roll shaft, as and for the purposes described.

16. The combination with an axle or shaft, 1, and a feed-roll shaft, of a counter-shaft 125 journaled on the shaft or axle, 1, of a pair of axles carrying press-wheels, a pair of sprock- 130 ets on the counter-shaft having operative connections with said press-wheel axles, a central sprocket-pinion on the counter-shaft and arranged between said sprocket-wheels thereon to be clutched to either of the same,

springs which act on the outside sprockets to normally force them into engagement with the central sprocket, and a sprocket-wheel on the feed-roll shaft and connected with the central sprocket-pinion, as and for the purposes described.

17. The combination with an adjustable drill and colter carrying mechanism and the feed-roll shaft, of the press-wheels mounted 10 independently of the drill and colter carrying mechanism, a transmitting mechanism intermediate the press-wheels and the feed-roll shaft, a clutch for making one member of the transmitting mechanism fast with the feed- 15 roll shaft, a shipper mechanism connected with said clutch, and means for operatively connecting the shipper with the drill and colter carrying mechanism, substantially as described.
18. The combination with a drill and colter carrying mechanism, and a feed-roll shaft, of the press-wheels, a counter-shaft, clutch-controlled gearing between the press-wheels and the counter-shaft, gearing between the counter-shaft and the feed-roll shaft, a clutch and shipper mechanism for making one member 25 of the last-named gearing fast and loose on the feed-roll shaft, and means for connecting the shipper with the drill and colter carrying 30 mechanism, substantially as and for the purposes described.
19. The combination with a feed-roll shaft, of a sprocket mounted loosely on said shaft, a clutch fitted to the shaft to make the sprocket 35 fast therewith, mechanism for rotating said sprocket, a spring-controlled shipper-rod having a loop or eye and connected with said clutch, a drill and colter mechanism, and a cam or wedge-bar movable with the drill and 40 colter mechanism in its vertical adjustment

and fitted normally in the eye or loop of the shipper-rod, substantially as described.

20. The combination with a feed-roll shaft, and a drill and colter carrying mechanism, of a counter-shaft arranged parallel to the feed- 45 roll shaft, sprocket-wheels mounted loosely on the feed-roll shaft and the counter-shaft and connected operatively together by an intermediate sprocket-chain, independent press-wheels, spring-controlled clutch and sprocket 50 wheels mounted on the counter-shaft and adapted to engage with the intermediate sprocket-wheel also fitted on said shaft, independent sprocket-chains connecting the press-wheels with the sprocket and clutch wheels 55 on the counter-shaft, a clutch connected with the sprocket-wheel of the feed-roll shaft, a shipper connected to said clutch, and a cam or wedge-bar attached to the drill and colter carrying mechanism and connected to the 60 shipper-bar, substantially as described.

21. The combination with a feed-roll shaft, and a lifter-bar of a seed-planter, of a power-transmitting gearing having one member thereof fitted loosely on the feed-roll shaft, a 65 clutch fitted to the shaft to engage said member of the power mechanism, a spring-controlled shipper-rod connected at one end to said clutch and carrying a loop or eye, and a cam or wedge-bar attached to said lifting-bar 70 and fitted to the eye or loop of the shipper-rod, as and for the purposes described.

In testimony that I claim the foregoing as my own I have hereto affixed my signature in the presence of two witnesses.

JAMES M. KING.
